UNITED STATES PATENT OFFICE.

HAROLD J. HORN, OF TRENTON, NEW JERSEY, ASSIGNOR TO JOHN A. ROEBLING'S SONS COMPANY, OF TRENTON, NEW JERSEY, A CORPORATION OF NEW JERSEY.

AEROPLANE STAY AND THE LIKE.

1,403,602.

Specification of Letters Patent. Patented Jan. 17, 1922.

Application filed May 23, 1918. Serial No. 236,132.

To all whom it may concern:

Be it known that I, HAROLD J. HORN, a citizen of the United States, residing at Trenton, county of Mercer, and State of New Jersey, have invented certain new and useful Improvements in Aeroplane Stays and the like, fully described and represented in the following specification and the accompanying drawings, forming a part of the same.

This invention relates to aeroplane stays and the like.

In certain structures such, for example, as aeroplanes, it has been found difficult to effectively anchor the ends of the stay wires, especially those of the flattened or stream line type.

It is the especial object of the present invention to provide means for properly and effectively anchoring the ends of such aeroplane stays, but the invention is applicable also to anchoring or attaching metal wires or bands of other forms, and for other purposes.

The present invention embodies a species of an invention more generically claimed in an application #236,133, filed May 23, 1918.

The following specification describes and the accompanying drawings illustrate various embodiments of the invention, it being understood that changes may be made in the form, construction and arrangement of the parts without departing from the invention.

In the drawings—

Figure 1 is a view in front elevation of stay anchoring means constructed in accordance with the invention.

Figure 2 is a view in side elevation of the same;

Figure 3 is a longitudinal section taken through Fig. 1, with parts omitted;

Figure 4 is an end view of Fig. 1;

Figure 5 is a cross-sectional view taken on the line 5—5 of Fig. 1;

Figure 6 is a view similar to Fig. 1 of a portion of a modified construction;

Figure 7 is an end view of the same;

Figure 8 is a view similar to Fig. 2, and

Figure 9 is a longitudinal section taken through Fig. 6.

For purposes of illustration, stays of the flattened or stream wire type are shown, and these stays are crimped, as hereinafter described, adjacent the end to be anchored. In structures embodying the invention, the

crimped portion of the stay is embraced by a plurality of anchoring members corrugated to correspond to the conformation of the stay, and these members are fastened in this interlocked relation with the stay. Although capable of various constructions, in the form shown in Figs. 1 to 5, a stay 15, crimped adjacent its end, as hereinafter described, is embraced between two anchoring members 16 and 17. These members, on one side, are corrugated to embrace the crimped stay in interlocking relation as clearly appears in Fig. 3. The outer surfaces of the anchoring members are rounded and somewhat flattened. To fasten these members in the interlocking relation described, they are bound together by a relatively large number of turns of a flexible binder 18, such as small wire, cord or the like, the ends of the binder being suitably secured as by being turned under at the ends. To aid in preventing the fastening binder from slipping, the anchoring members are slightly dished to form shoulders, as at 19 and 20, which serve as stops to engage the binder. With such a construction, the stay is securely and firmly held in interlocking relation with the anchoring members which are fastened in place so as to be substantially immovable.

Means is provided for connecting the anchored stay with a terminal which may be any portion of the aeroplane or other structure to which the stay is to be secured, and in structures embodying the invention to the best advantage, the anchoring members themselves are connected with the terminal and the connection includes a universal joint. Although capable of various constructions, in the present embodiment the terminal which is, for example, a frame bar 21, is embraced by a forked lug 23 secured in place by a pivotal pin 22 on which the lug swings, this lug being formed on the end of a connecting stem 24 which is threaded through the collar 25 of a member having a swinging connection with the anchoring members. Extending out from opposite sides of the collar 25 are curved wings 26 which are received in slots 27 formed in wing portions 28 bowed outwardly from the anchoring members, as shown more clearly in Fig. 1. The slots 27 permit the winged member 25 carrying the connecting stem to swing loosely as if about a pivot, its movement being limited by the engagement of 100

105

110

either wing 26 with the anchoring members. The plane in which the winged member 25 swings is at right angle to the plane of the forked lug 23 and consequently there is a universal joint connection between the anchoring members and the terminal.

To adjust this connection, to take up slack or the like, the connecting stem 24 is moved relatively to the collar 25, by means of its 10 threaded relation therewith, and a lock nut 30 is provided to hold the parts in the desired position.

The invention includes provision for obtaining the full strength of the wire and for 15 distributing the strain on the crimps. This is accomplished by varying the degree of the crimps, and in structures embodying the invention to the best advantage, the crimps gradually increase in degree. As more 20 clearly appears in Fig. 3, the stay wire 15 is shown formed adjacent its end with a plurality of crimps, which, as will be apparent, vary in degree. The first crimp 31 is relatively slight, its angle being not far from 25 a straight line. The next crimp 32 is slightly more pronounced, and this increase in degree is gradual until the final crimp 33 at the end of the stay is fairly sharp. It will be understood that the precise number 30 of crimps is immaterial. With a construction such as that described, when the stay is anchored and secured in place, the strain on the first crimp is not excessive, the strain being distributed throughout the crimped 35 portion. As a result, the full strength of the wire is obtained.

Figs. 6 to 9 illustrate a modification in which the anchoring members are interlocked at their forward ends. The stay 15, 40 crimped as before described, is embraced between anchoring members 40, 41 corrugated to correspond to the conformation of the crimped stay and fastened in place by flexible binder 18 in the same manner as before 45 described.

The invention includes means for interlocking the forward ends of the anchoring members, and in structures embodying the invention to the best advantage, the anchoring members have intercrossing portions through which the stay passes. Although capable of various constructions, in the form shown one of the anchoring members, for example, the one designated as 40, is formed 55 at its forward end with an oblique inwardly extending tongue 42. As this tongue extends across the path of the stay, when the anchoring member is in position, it is formed with a suitable opening 44 for the 60 passage of the stay. The other anchoring member 41 is provided at its forward end with a hook-shaped tongue 45 extending across the path of the stay, and provided with an opening 46 for the passage of the 65 stay. This anchoring member 41 is also

formed with a transverse slot 47, for the reception of the tongue 42 of the other anchoring member. When the parts are in place the tongue 45 of the anchoring member 41 hooks over the outer end of the 70 anchoring member 40, the tongue 42 of the latter entering the transverse slot 47 and the stay passes through the openings in these intercrossing tongues to effectively interlock the ends of the two anchoring members. 75

In Figs. 6 to 9 only the forward portion of the device is illustrated, as the remainder is identical with that shown in Figs. 1 to 5.

What is claimed is:

1. In securing means for aeroplane stays and the like, a stay formed adjacent its end with crimps of varying degree, a plurality of anchoring members correspondingly formed to embrace the crimped portion, and a flexible binder for fastening said anchoring members in interlocking relation with the crimped stay. 80

2. In securing means for aeroplane stays and the like, a substantially rigid and non-flexible stay crimped adjacent its end, a plurality of anchoring members correspondingly formed to embrace the crimped portion, and a flexible binder for fastening said anchoring members in interlocking relation 90 with the crimped stay. 95

3. In securing means for aeroplane stays and the like, a terminal, a stay formed adjacent its end with crimps of varying degree, a plurality of anchoring members correspondingly formed to embrace the crimped portion, a flexible binder for fastening said anchoring members in interlocking relation with the crimped stay, and means for connecting the anchored stay with said terminal. 100

4. In securing means for aeroplane stays and the like, a terminal, a stay formed adjacent its end with crimps, a plurality of anchoring members correspondingly formed to embrace the crimped portion, means for fastening said anchoring members in interlocking relation with the crimped stay, means for connecting said anchoring members with said terminal including slotted wings associated with said anchoring members and a winged member mounted to swing in said slots. 115

5. In securing means for aeroplane stays and the like, a stay crimped adjacent its end, a plurality of anchoring members correspondingly formed to embrace the crimped portion and interlocked at their ends, and a flexible binder for fastening said anchoring members in interlocking relation with 120 the crimped stay. 125

In testimony whereof, I have hereunto set my hand.

HAROLD J. HORN.
